DESIGN FOR A PORTABLE COLLAPSIBLE
MOTION PICTURE PROJECTION SCREEN
STAND

Harry E. Eller, Chicago, Ill.

Application November 18, 1946, Serial No. 134,867

Term of patent 3½ years

(Cl. D61—1)

To all whom it may concern:

Be it known that I, Harry E. Eller, a citizen of the United States, residing in Chicago, in the county of Cook and State of Illinois, have invented a new, original, and ornamental Design for a Portable Collapsible Motion Picture Projection Screen Stand, of which the following is a specification, reference being had to the accompanying drawing, forming part thereof.

Fig. 1 is a perspective view of a portable collapsible motion picture projection screen stand, showing my new design;

Fig. 2 is an enlarged cross-section of the post taken on line 2—2 of Fig. 1;

Fig. 3 is an enlarged cross-section of one of the collapsible supporting legs taken on line 3—3 of Fig. 1;

Fig. 4 is an enlarged cross-section of one of the leg brace members taken on line 4—4 of Fig. 1;

Fig. 5 is an enlarged cross-section of the screen casing handle taken on line 5—5 of Fig. 1.

Fig. 6 is a rear elevation of the screen casing and handle therefor;

Fig. 7 is a top plan view of the screen casing and handle therefor;

Fig. 8 is a front elevation of the screen casing and handle therefor; and

Fig. 9 is an enlarged perspective view of the screen casing handle.

The essential features of my design reside in the portions shown in full lines.

I claim:

The ornamental design for a portable collapsible motion picture projection screen stand, substantially as shown and described.

HARRY E. ELLER.
